UNITED STATES PATENT OFFICE.

ANDREW BARNA, JR., OF CHICAGO, ILLINOIS.

IGNITION TESTER.

Application filed May 25, 1922. Serial No. 563,535.

This invention relates to new and useful improvements in ignition testers, specifically adapted for application to the ignition system of internal combustion engines employed in all types of combustion engine vehicles.

The primary object of this invention is the production of an ignition tester that may be readily supported on the dash board of a motor vehicle so as to be readily viewed at all times by the operator of the same.

A further object of this device is to readily enable the operator of a motor vehicle to determine at all times whether or not the ignition to the several spark plugs of a motor is functioning properly, this tester permitting the operator of the vehicle to ascertain whether the trouble be in one of the plugs of the engine or in the feed wires from the distributor or within the distributor itself.

A still further object of this invention is the production of such a device that is both easy and inexpensive of manufacture and a device that may be readily installed upon any motor vehicle employing the usual type of internal combustion engine.

With the above and other objects in view, the invention consists of the novel form, combination and arrangement of parts hereinafter more fully described, shown in the accompanying drawing and claimed.

In the drawing, wherein like reference characters designate corresponding parts throughout the several views,

Figure 1 is a front elevational view of the tester, the same being removed from the dash board,

Figure 2 is a top plan view of the same,

Figure 3 is a longitudinal sectional view upon the broken line III—III of Fig. 1,

Figure 4 is a transverse sectional view upon the broken line IV—IV of Fig. 2 and showing the ignition wires secured in position, and further showing one of the switch blades partly in section and in an extended dotted line position,

Figure 5 is a rear elevational view of the device shown in Fig. 1,

Figure 6 is a detail perspective view of one of the switch blades, and

Figure 7 is a similar view of the top wall of the casing.

Referring more in detail to the several views a rectangular casing 1 of a suitable insulating material is so molded to provide

a plurality of compartments 2 in the front wall thereof. Secured to the front wall of the compartment 1 by set screws 3 or the like is a plate member 4 of relatively greater dimensions than the casing 1. This plate is provided at its opposite end portions with enlarged perforations 5 for receiving any desired form of fastening means whereby the casing 1 and the plate 4 may be readily secured within a rectangular opening in the dash board of a motor vehicle (not shown). The plate 4 is provided with a rectangular opening 6 therethrough, which opening is in alinement with the compartments 2 in the casing 1 and rigidly held between the adjacent faces of the front plate 4 and casing 1 there is disposed a rectangular strip of glass 7 whereby the compartments 2 within the casing 1 may be readily viewed. The casing 1 is provided on its rear side with an upper and lower longitudinally disposed series of bores 8 and 9 respectively, the inner ends of these bores communicating with the compartments 2. Positioned within the upper bores 8 of the casing 1 are insulated lead wires 10 from the distributor head. The extreme ends of these wires within each compartment 2 is secured within the compartment by bending the same around depending set screws 11 and it is to be noted that these set screws project through the upper wall of the casing 1, the heads 12 of these screws being flush with the outer surface of the said upper wall. Similarly positioned within the lower row 9 of the perforations in the casing 1 are other insulated lead wires 13 from the spark plugs of the combustion engine, and the extreme ends of these wires projecting into the compartment 2 are secured therein by threaded set screws 14 within each compartment, these set screws being suitably spaced from the lower ends of the before-mentioned set screws 11.

The upper wall of the casing 1 is transversely slotted as at 15 above each compartment 2 within the casing, and positioned within each of these slots is a flat like switch blade 16 of insulating material. Positioned upon the top wall of the casing 1 and the upper surface of the switch blades 16 is a cover plate 17 of rectangular formation and of the same dimensions as the upper wall of the casing. This cover plate 17 is rigidly secured to the said surface of the casing 1 by screws or the like fastening means 18 re-

ceived within openings 19 at the four corners of the plate. The front plate 4 of the casing 1 is provided with openings 20 in alinement with the forward ends of the 5 slots 15 of the casing 1 for permitting passage of the switch blades 16 therethrough. It will therefore be seen that the said switch blades are slidably disposed within the said slots of the casing 1 and are loosely retained 10 therein for sliding movement by the cover plate 15. Each end of these blades 16 is provided with an end cap 21 secured thereto by screws 22, and it will be noted that the length of these end caps is slightly greater 15 than the width of the switch blades 16 for preventing removal of these switch blades from their position within the slots.

The undersurface of the rectangular cover plate 17 is provided with a longitudinal 20 strip 23 of some conducting material such as brass, copper or the like and this strip of such material is positioned within the said face of the plate 17 so as to overlie the upper ends 12 of the binding set screws 25 11 within each compartment 2. This strip 23 is held by any suitable retaining means within the plate 17 and centrally positioned through the strip and also passing through the cover plate 15 is a binding post 24 projecting externally of the plate and to which there is secured by a lock nut 25 one end 30 of a ground wire 26. The opposite end of this wire is suitably secured to the frame of the motor vehicle whereby the circuit therethrough is grounded. Each switch blade 16 is provided with a conducting screw 27 therethrough at a point spaced from the inner end of the said strip. The opposite ends of each screw 27 are flush with the 35 adjacent surfaces of the blade 16, and are so positioned as to contact with the heads 12 of the screws 11 and the longitudinal strip 23 of the cover plate 17 when the switch blades 16 are slid to their dotted 40 line position shown in Fig. 4.

From the above description it will clearly be seen that when the switch blades 16 are in the position shown in Fig. 2 and by the full lines of Fig. 4 the electric current from 50 the storage battery to the distributor head, not shown and from the point within this head through each wire 10 to the set screw 11 will cause a consequent jump and a spark between the adjacent ends of the set screws 11 and the head of the post 14 within each 55 compartment 2 and then through the plug leads 13 to the spark plugs within the cylinders when there is no interruption in the circuit due to bad points within the distributor or to broken or fouled plugs. While the motor is running idle and should a spark jump be noted in each compartment 2 it will naturally be known that there is 60 no fault with the distributor or within the lead wires from the distributor nor within

the plug leads 13 to the spark plugs. Should, however, one of the plugs be fouled or there be trouble within a separate circuit to any one of the plugs, a spark jump between the set screw 11 and the binding post 14 will not be seen. And again, while the motor is running idle should the operator detect a miss in any one of the cylinders and at the same time there would be visible a spark jump within each one of the 75 compartments he may accurately determine broadly where the trouble lies, by sliding any selective one of the switch blades 16 into the dotted line position of Fig. 4, and after any one of these switch blades are 80 moved to such a position should the motor still sound the same, it will be readily noted by the operator that something is wrong somewhere in the circuit for that respective cylinder. This fact being determined by 85 shunting the circuit through the distributor lead 10, set screw 11, head 12, connecting screw 27 within the switch blade 16 and thence through the strip 23 to the ground wire 26 for cutting out the jump within the 90 respective compartments and the consequent circuit through the coating plug lead 13 to one of the plugs within the motor.

Minor changes may be made in the invention without departing from the spirit 95 and scope thereof as claimed.

What is claimed as new is:—

In a device of the kind described, a base of insulating material having a series of 100 rectangular transverse slots extending from front to back thereof in its top wall, a cover for said base having a recess in its under side extending longitudinally thereof above and communicating with the series of transverse slots, said base being provided 105 with a plurality of compartments in its front portion below the series of transverse slots and forming spark chambers, spaced pairs of bores leading from each of said spark chambers through to the rear face of 110 the block, a fixed contact strip fitting in the longitudinal recess of said cover and adapted for connection to a ground, combined contact members and terminals each extending through an aperture in the bottom of the series of transverse slots and into said spark chambers and being in vertical alinement with the contact strip, the upper ends of 115 said terminals being flush with the bottoms of the series of transverse slots, contact 120 blades of insulating material slidable in the series of transverse slots and each having a contact member extending vertically therethrough with its ends flush with the upper and lower faces of said blades, and other terminals fixed to the rear face of the 125 spark chambers in spaced relation to the first terminals.

In testimony whereof I affix my signature,
ANDREW BARNA, JR.
